UNITED STATES PATENT OFFICE.

GEORGE J. ABERNATHY, OF AMBROSE, TEXAS, ASSIGNOR OF ONE-HALF TO T. E. AMOS,
OF AMBROSE, TEXAS.

JACK.

1,168,141.

Specification of Letters Patent. Patented Jan. 11, 1916.

Application filed February 13, 1915. Serial No. 8,012.

To all whom it may concern:

Be it known that I, GEORGE J. ABERNATHY, a citizen of the United States, residing at Ambrose, in the county of Grayson and State of Texas, have invented new and useful Improvements in Jacks, of which the following is a specification.

This invention relates to jacks, especially adapted for use upon motor cars and similar vehicles, and has for its primary object to provide a jack of this character, which may be folded into a compact condition, for storage, within the tool chest of the machine. A further object of the invention is to provide a device of this character, in which the unfolding of the jack will cause the same to assume its normal working position, and also moves the operating lever for the jack to its normal or starting position within convenient reach of the operator of the jack.

A further object of the invention is to provide a jack of the character described in which the slide block to which the load imposed upon the jack is attached is drawn to its normal or lower-most position by the folding of the jack.

A further object of the invention is to provide a device of the character described which is simple in construction, cheap to manufacture and highly efficient in use.

The invention consists in the improved construction and novel arrangement and combination of parts which will be herein-after fully described and particularly pointed out in the claims.

The preferred embodiment of the invention has been illustrated in the accompanying drawing, but no restriction is necessarily made to the precise details of construction therein shown, as changes, alterations and modifications within the scope of the claims may be resorted to when desired.

In the drawings:—Figure 1 is a perspective view of the invention applied to the rear axle of a motor vehicle and in the initial position for raising the same. Fig. 2 is a side elevation of the invention showing a portion of the rear axle of the motor vehicle connected thereto and in a raised position. Fig. 3 is a longitudinal sectional view showing the jack detached from the axle of the motor vehicle and in a folded condition.

Fig. 4 is a cross section on the line 4—4 of Fig. 2.

Like characters of reference denote corresponding parts throughout the several views.

The numeral 1 designates a portion of a motor vehicle and the rear axle connected therewith, the said axle being connected as at 2 with the jack constructed in accordance with the invention.

The jack proper comprises a pair of channeled sections 3 and 4. The sections 3 and 4 are united to provide a standard by means of a hinge joint, as at 5, and upon the pintle pin 6 of said hinge joint is mounted an operating lever 7 having a fork end 8. The fork end 8 of the lever 7 is provided adjacent its connection with the pintle pin 6 with perforated ears 9. The upper channeled section 4 is slotted as at 10 upon opposite sides thereof while the lower channeled section 3 is provided with a base portion 11 having a spring clip 12 thereon for engagement with the standard 4 when the same is in a folded position. Mounted for sliding movement upon the upper channeled section 4 is a U-shaped load carrying block 13 secured to the section 4 by means of a pin 14 passing through the slots 10 in said section, and a plate 15 bolted upon the ears 16 of the load carrier 13. The ears 16 of the load carrier 13 are further provided with openings 17, said openings being adapted to receive the threaded ends of the U-shaped clips 18 which are passed around the axle 1 of the motor vehicle secured to the ears 15 by means of bolts 19, thereby securing the load carrying block to the weight to be lifted.

Eccentrically connected as at 19 to the ears 9 of the fork lever 7 is a link 20 having one end thereof secured by the pin 14 to the load carrying block 13. The load carrying block 13 is adapted to engage recesses 22 formed in the channeled sections 3 when the standard 4 is in a folded position.

From the foregoing description taken in connection with the accompanying drawing it is readily apparent that when the section 4 is moved to an upright position and the weight to be lifted connected with the load carrying block 13 and the fork lever 7 moved to a lowered position as shown in Fig. 2, an

effectual jack will be provided. Furthermore it will be seen through the link connection with the lever 7 when said lever is in its lowered position and the weight attached to the block 13, the back of the standard 3 being in engagement with the lever 7 sustains the weight upon the block 13 in a raised position. It is also obvious that when the jack is unfolded the action of 5 the link 20 upon the lever 7 forces the same into an upright position thereby bringing it within convenient reach of the operator for raising the load imposed upon the jack, and furthermore through the action of this 10 same link upon the lever 7, in closing the jack the block 13 will be brought to its lowermost or normal position.

Having thus described my invention what is claimed as new, is:—

- 20 1. A jack comprising a channeled standard formed from sections which, when united, provide a hinge joint including a pintle, a load carrying block slideable upon one of the sections, a forked lever mounted upon said pintle, and a link eccentrically connecting said lever with the load carrying block.
- 25 2. A jack comprising a channeled standard formed from sections hingedly connected together by means of a pintle intermediate the ends of the standard, a load carrying block slideable upon and within one of said standards, a forked lever mounted

upon the above mentioned pintle, and a link eccentrically pivoted to said lever and connected with the load carrying block. 35

3. A jack comprising channeled sections adapted, when united, to form a standard having a hinge joint intermediate the ends thereof, one of said sections being provided 40 with alined slots, a load carrying block slideable upon one of the channeled sections and in said slots, means for connecting the load to said block, a lever having a forked end fulcrumed upon the standards, and a link 45 connecting the forked end of said lever with the load carrying block.

4. A jack comprising a pair of channeled sections adapted, when united end to end, to provide a standard having a hinge joint intermediate the ends thereof, a spring latch upon one of said sections, a load carrying block slideable upon one of said sections, an operating lever pivotally connected with the standard, and a link connecting the lever and load carrying block, said lever and link 55 coöperating when the jack is folded to restore the load carrying block to its normal position.

In testimony whereof I affix my signature 60 in presence of two witnesses.

GEORGE J. ABERNATHY.
